US00D897613S

(12) **United States Design Patent** (10) **Patent No.:** **US D897,613 S**
(45) **Date of Patent:** **** Sep. 29, 2020**

(54) **INCUBATOR FOR ANIMAL**

(71) Applicant: **AUTO ELEX Co., LTD**, Gimhae-si, Gyeongsangnam-do (KR)

(72) Inventor: **Jong-yoon Bae**, Gimhae-si (KR)

(73) Assignee: **AUTO ELEX Co., LTD**, Gimhae-si (KR)

(**) Term: **15 Years**

(21) Appl. No.: **29/727,887**

(22) Filed: **Mar. 13, 2020**

Related U.S. Application Data

(60) Division of application No. 29/624,358, filed on Oct. 31, 2017, which is a continuation of application No. 29/590,655, filed on Jan. 12, 2017, now Pat. No. Des. 827,903.

(57) **CLAIM**

I claim the ornamental design for an incubator for animal, as shown and described.

DESCRIPTION

FIG. 1 is a perspective view of an incubator for animal showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the incubator for animal in an open configuration.

The broken lines shown throughout the views depict unclaimed portions of the design and form no part of the claimed design.

1 Claim, 8 Drawing Sheets
